DESIGN FOR A HAIR WAVING MACHINE

Jack P. Fischer, Scarsdale, and Maximilian Ehrlich, Woodmere, N. Y.

Application May 8, 1941, Serial No. 100,851

Term of patent 7 years

To all whom it may concern:

Be it known that we, Jack P. Fischer and Maximilian Ehrlich, citizens of the United States and residents respectively of the cities of Scarsdale and Woodmere, in the counties of Westchester and Nassau, State of New York, have invented a new, original, and ornamental Design for Hair Waving Machines, of which the following is a specification, reference being had to the accompanying drawing, forming part thereof.

Fig. 1 is perspective view of a hair waving machine showing our new design.

Fig. 2 is a perspective view of the same device as seen from the rear of Fig. 1.

Fig. 3 is a top plan view thereof.

We claim:

The ornamental design for a hair waving machine, as shown.

JACK P. FISCHER.
MAXIMILIAN EHRLICH.
